UNITED STATES PATENT OFFICE.

HENRY MELLOR, OF HOLYOKE, MASSACHUSETTS.

PAPER-PULP DRESSING AND EVENING DEVICE.

SPECIFICATION forming part of Letters Patent No. 645,422, dated March 13, 1900.

Application filed April 7, 1899. Serial No. 712,123. (No model.)

To all whom it may concern:

Be it known that I, HENRY MELLOR, a subject of the Queen of Great Britain, residing at Holyoke, in the county of Hampden and State 5 of Massachusetts, have invented new and useful Improvements in Paper-Pulp Dressing and Evening Devices, of which the following is a specification.

This invention relates to paper-making machines, the object being to provide for operation in connection with said machines improved pulp evening or dressing devices adapted to act upon the pulp between the pulp-screens and the Fourdrinier wire-cloth of the 15 paper-making machine to prevent the delivery upon said wire-cloth of the paper-machine of any accumulation or bunches of pulp, which in the completed paper will appear as more or less thickened dark-colored spots in said 20 paper and sometimes under the effect of the pressure of calendering or other rolls will work perforations or thin spots in the paper, thereby seriously damaging the latter; and the invention consists in interposing suitable 25 devices between said screens and the paper-machine which so act upon the paper-pulp while moving from the said screens onward to the machine that all bunch-like collections and accumulations of parts of the pulp are 30 destroyed and are reduced to the consistency of the main body of the pulp, so that the delivery thereof to the paper-machine consists of a clear mat of pulp of equal thickness and free from any of said objectionable bunch- 35 like collections and said damage to and consequent waste of paper is avoided, all as hereinafter fully described, and more particularly pointed out in the claims.

In the drawings forming part of this specification, Figure 1 is a vertical sectional view 40 between the ends of a pulp-receiving box containing devices for acting upon paper-pulp prior to the delivery of the latter onto a paper-machine constructed according to my invention, said figure showing a portion of a paper-machine adjacent to the pulp-delivery spout of said box, the latter showing an inlet thereon through which pulp is received from the pulp-screens. Fig. 2 is a vertical sectional 45 view of said pulp-receiving box near one side thereof, showing cylinders in side elevation

therein for action upon pulp passing therethrough.

Referring to the drawings, A indicates a portion of the end of the frame of a paper-making machine, and B a section of the supporting-roll over which the Fourdrinier wire-cloth runs at or near said end. D indicates a suitable box for receiving wet paper-pulp from the ordinary pulp-screens, a portion 55 of one of which is indicated by S, through which the pulp passes before it is delivered onto said paper-machine, and E indicates a portion of a pipe connection between said box and screens, through which the pulp may flow 60 into said box D. F² indicates a spout connected with a part D' of said box, through which the pulp flows from the latter onto the said paper-machine in the direction indicated by the arrows x, Fig. 1. The level of the 65 bottom of the spout F² is, as in all machines of this class, somewhat below the level of the overflow from the screen-boxes, and as this overflow is conducted to the bottom of the box D through the pipe E it follows that the 70 pulp and water will flow up through the said box D without assistance from the revolving rolls, the revolutions of which, as will be described farther on, serving, however, to give a certain circuitous direction to the course of 75 the pulp passing through the box D. It is well known that paper-pulp has a tendency to ball up during the refining process thereof, and this invention provides means for brushing out any of said pulp balls or bunches as 80 may pass through the screens before the pulp flows onto the wire of the paper-machine, thereby insuring a more perfect product. The above-referred-to devices which act upon the 85 paper-pulp, as aforesaid, while moving from the screens to the paper-machine are located 90 within said box D and comprise the below-described devices, which are located in and attached to the sides of said last-named box. Several rolls F F F', (three being the preferred number,) having suitable supporting-shafts, are hung one above the other in suitable bearings in the ends of said box, so that they may be rotated by a belt applied to a pulley h on a shaft of one of said rolls, the 95 shafts of the other two rolls being gear-connected to that one bearing said pulley. Thus 100

said three rolls have uniform rotary movements; but the upper and lower rolls F F rotate in opposite or dissimilar directions from the center one. Said three rolls have each of them a series of longitudinal metal blades *h*, extending from end to end thereof, the outer edges *o* of which project, as shown, beyond the body *i* of the roll, (see Fig. 1,) which body is preferably of wood, in which the inner edges of said blades are inserted, as shown, and said blades are held against end movement by an end plate *k*, secured against each end of the roll. The said outer edges *o* of said blades are preferably made thinner than the adjoining inner portions, as shown, thereby providing portions for such mutual action against said pulp bunches as best secures the breaking up of said bunches. In practice the upper and lower rolls F F are adjusted for rotation so that the edges of the blades thereof shall move very near the edges of the blades of the intermediate roll F, but having no contact therewith. The blades of the center roll F lie parallel with the axis of the latter, and the blades of the top and bottom rolls F have their blades arranged in lines diagonal to the axis of said rolls, whereby even though the contiguous edges of the blades of the rolls may be moving in the same direction there will be a shearing action on the pulp passing between them which will tend to draw out the pulp balls or bunches and separate the fibers. The above-described diagonal arrangement of the blades of certain of the rolls will cause the pulp in passing between the latter to take a diagonal course, whereby it will be longer subjected to said drawing-out action. Said devices for acting upon the pulp for the purpose aforesaid comprise also one or more knife-bars *J*, extending longitudinally on the inner walls of said box D opposite each of said rolls. Said bars *J* are each held in a slotted or grooved support *r*, suitably secured to said box-walls, in which said bars may have a certain adjusting movement toward and from the face of said rolls, which movement is imparted thereto by one or more adjusting screw-bolts *n* for each bar, each of which passes through a nut *v*, fixed to the outer side of said box, and a set-nut *e* for each screw-bolt *n*, whereby said screws are held against displacement after having been adjusted. Each of said bars *J* has a longitudinal T-shaped slot in its inner face or side, in which are engaged the inner ends of said screw-bolts *n*, as shown, whereby such connection of screws and bar is had as permits the free rotation of said screws, whereby by the operation of the latter the bar *J* is positively moved toward and from said roll or rolls. The face of each of said bars *J* adjoining said rolls is preferably slightly concaved in accordance with the circle described by the movement of the edges of the roll-blades, and said bar-face is longitudinally slotted, as shown, thereby producing on each of said bars a series of knife-blades *m*, simi-

lar to the edges of said blades *h*. The operative positions of said bars *J*, carrying the said blade-like ribs *m*, is one which brings the edges of said ribs *m* very close to, but not in engagement with, the outer edges of the blades on the said rolls, to the end that the action of the roll-blades and of said ribs *m* upon the pulp bunches shall be substantially like that of the blades of two of said rolls, as above described. Thus it will be seen that the pulp from the screen-box S entering the roll-containing box D through the conduit E will, because of the described arrangement of the rolls and bars *J*, be caused to follow the course indicated by the arrows *z*, which causes it to be exposed three times to the combined action of a roll and bar *J* and twice to the action of the three blade-carrying rolls, such actions serving to effectually dissipate any bunches contained in the pulp when entering said box D, as described. Upon leaving the last-named box the pulp, as aforesaid, follows the course indicated by the arrows *x* through said box part D' and passes through the spout F² onto the paper-machine.

Having thus described my invention, what I claim, and desire to secure by Letters Patent, is—

1. The combination with the wire-cloth of a paper-machine and screen-box therefor, of a box located between said wire-cloth and screen-box, a conduit between the latter and the bottom of said box, a series of rolls mounted one above the other in said box, radial blades on said rolls, knife-bars set adjustably in close proximity to the edges of said blades, means for rotating contiguous rolls of said series in opposite directions, whereby pulp passing up through said box is made to take a circuitous direction, and an outlet from said box above the surface of said wire-cloth, substantially as described.

2. In combination with the wire-cloth of a paper-machine, and a screen-box for the latter, pulp dressing or evening devices comprising a box located between said wire-cloth and screen-box, through which wet paper-pulp passes on its way to, and before reaching said machine, knife-bars set horizontally in the inner wall of said box, several revoluble rolls supported in said box in parallelism with said bars for simultaneous rotary movements, certain ones thereof rotating in opposite directions to others, each of said rolls having a series of radially-disposed longitudinal blades, those on one roll being parallel with, and on the next inclined to, the axis of said rolls, whereby pulp in passing between the latter will be given a direction of movement diagonal to said rolls, and means for imparting said rotary movements to the rolls, substantially as described.

3. In combination with the wire-cloth of a paper-machine, and a screen-box for said machine, of pulp dressing or evening devices comprising a box located between said wire-cloth and said screen-box through which pulp

passes in an upward direction on its way to said machine, knife-bars set horizontally in the inner wall of said box, several revoluble rolls supported in said box in parallelism with 5 said bars for simultaneous rotary movement, certain ones of said rolls rotating in opposite directions to others, each of said rolls having a series of radially-disposed longitudinal blades, means for imparting said rotary movements to said rolls, whereby said pulp is made to take a circuitous direction through said box and between the several rolls, and an overflow-outlet from the latter above the said wire-cloth, substantially as described.

15 4. In combination with the wire-cloth of a paper-machine, and a screen-box for said machine, of pulp dressing or evening devices comprising a box located between said wire-cloth and said screen-box through which pulp

passes in an upward direction on its way to 20 said machine, several revoluble rolls supported in said box for simultaneous rotary movements, certain ones of said rolls rotating in opposite directions to others, each of said rolls having a series of radially-disposed longitudinal 25 blades, a series of knife-bars supported on the inner walls of said box, and adjustable toward and from said rolls, means for imparting said rotary movements to said rolls, whereby said pulp is made to take a 30 circuitous direction through said box and between the several rolls, and an overflow-outlet from the latter above the said wire-cloth, substantially as described.
